TROUBLE LIGHT

Edward J. Smith, Clifton, N. J.

Application July 8, 1949, Serial No. 3,803

Term of patent 14 years

(Cl. D48—20)

To all whom it may concern:

Be it known that I, Edward J. Smith, a citizen of the United States, residing at 54 Lindale Court, city of Clifton, in the county of Passaic and State of New Jersey, have invented a new, original, and ornamental Design for Trouble Light, of which the following is a specification, reference being had to the accompanying drawing, forming a part hereof.

In the drawing:

Fig. 1 is a side elevational view of a trouble light showing my new design;

Fig. 2 is a top plan view thereof, the magnet keeper being shown removed from the magnet;

Fig. 3 is a bottom plan view;

Fig. 4 is an elevational view looking at the left end of Fig. 2, the figure being turned through an angle of 90°; and

Fig. 5 is an elevational view looking at the right end of Fig. 1.

The dotted lines shown in the drawing are for illustrative purposes only.

I claim:

The ornamental design for a trouble light, as shown and described.

EDWARD J. SMITH.
